UNITED STATES PATENT OFFICE.

MADISON D. SHIPMAN, OF DE KALB, ILLINOIS.

DESIGN FOR A SOCKET MEMBER FOR DETACHABLE FASTENERS.

SPECIFICATION forming part of Design No. 31,350, dated August 8, 1899.

Application filed March 3, 1898. Serial No. 672,470. Term of patent 14 years.

To all whom it may concern:

- Be it known that I, MADISON D. SHIPMAN, a citizen of the United States, residing at De Kalb, in the county of De Kalb and State of Illinois, have invented and produced a new and original Design for the Socket Members of Detachable Fasteners; and I do declare the following to be a full, clear, and exact description of the same.
- 10 This invention relates to designs for detachable fasteners for gloves and other articles; and the invention consists of a design for the socket member of a detachable fastener, as shown in the accompanying drawings, in which—
- 15 Figure 1 represents a top or plan view of the device, and Fig. 2 a side elevation of the same, both views being taken on an enlarged scale.
- 20 The socket member shown comprises a cap or button-head A, having a base portion or washer B, connected therewith by the sleeve C, which extends through an opening in the material to which the device is attached, the
- 25 cap being located on the upper side or exposed surface of the material and the washer on the

lower or opposite side thereof. The cap or button-head has its exposed surface or top ornamented, as shown, by a series of reversely-arranged scrolls or spirally-flowing lines a , 30 curving alternately to the right and left or in opposite directions, and scalloped lines a' and a'' , encircling the scrolls and having their concave sections or portions faced or turned toward the scrolls which are arranged between the scallops. The outer scalloped line is encircled by a series of dots a^3 , and a similar series of dots a^4 is arranged within the circle of the inner scallops. The outer marginal portion b of the washer has a convex 40 ring-like form.

What I claim is—

The design for the socket member of a detachable fastener, substantially as herein shown and described.

45 In testimony whereof I affix my signature in presence of two witnesses.

MADISON D. SHIPMAN.
